MECHANICAL MOVEMENT

Sidney J. Finn, Beverly, Mass., assigner to United
Shoe Machinery Corporation, Flemington,
N. J., a corporation of New Jersey

Application July 5, 1944, Serial No. 543,533

5 Claims. (Cl. 74—110)

This invention relates to mechanical movements and more particularly to mechanisms for transmitting rectilinear movement from one member along one path to another member along a path disposed at an angle to the path of movement of the first member.

One commonly employed form of mechanism for transmitting motion in this manner involves the use of gearing between the drive and driven members. This type of mechanism is generally satisfactory, but in applications where extreme accuracy and absence of lost motion between the drive and driven members is essential, great care is required in cutting the gears used and in assembling the mechanism. Another objection to the use of gearing in certain applications is the lack of sufficient space to house the gearing required.

In order to avoid the above objections a fluid transmission system may be provided between the drive and driven members. With such a system it is possible without any great difficulty to eliminate lost motion between the drive and driven members. Such a system, however, requires the use of suitable pistons and packings and occasional replenishment of the fluid in the system.

An object of the present invention is to provide a mechanical movement embodying improved means for transmitting rectilinear motion of one member to another along paths at angles to each other, which is simpler in construction than mechanisms heretofore employed, and overcomes the disadvantages of mechanisms of the types outlined above. To this end and in accordance with a feature of the invention, the motion-transmitting mechanism comprises a series of anti-friction elements movable positively in either of two directions by one of the members, the elements being confined for movement in a curved path, the outer portions of which are parallel to the path of movement of said one of the members and another portion of which is parallel to the path of movement of the other member, the other member being provided with an element interposed between a pair of anti-friction elements in said other portion of the path so that movement of the elements by one of the members along one path causes movement of the other member along the other path.

The above and other features of the invention will now be described by reference to the accompanying drawing and pointed out in the claims.

In the drawing,

Fig. 1 is a plan view of one form of mechanism in which the invention may be embodied;

Fig. 2 is a section on the line II—II of Fig. 1;
Fig. 3 is an elevation of a modified form of the mechanism of Fig. 1, and

Fig. 4 is a section on the line IV—IV of Fig. 3.

Referring to Fig. 1 a driven member in the form of a bar 10 is mounted for movement in a guideway formed in the upper portion of a block or support 12 and held in position therein by a cover plate 14. The bar 10 is arranged to be moved rectilinearly along the guideway in the block 12 by movement of an actuating member 16 movable at right angles to the path of movement of the bar 10. The actuating member 16 is guided for movement with respect to the block 12 by pins 18, 20, carried by arms 22 of the member 16 slidably in aligned bores formed at the ends of a curved bore 23 in the block 12. For transmitting motion from the member 16 to the member 10, a series of anti-friction members 24 which may be in the form of rolls are guided for movement along a curved path in the bore 23 in the block 12, the outer portions of the path being parallel to the path of movement of the member 16 and the intermediate portion of the path being of U-shape, the legs of the U being parallel to the path of movement of the bar 10. One of the rolls 24 as shown in Fig. 2 is carried by and depends from the bar 10 and the outermost rolls are engaged by the inner ends of the pins 18 and 20.

From the above it will be seen that as the member 16 is moved it will cause movement of the rolls 24 along the curved path and the motion of the rolls is transmitted by connection of one of the rolls to the bar 10 thereby to move the bar at right angles to the path of movement of the member 16. In order to avoid any lost motion and to facilitate assembly of the mechanism the pin 18 is illustrated as being formed at the inner end of a screw 26 threaded through one of the arms 22 of the actuating member 16. A lock nut 28 is provided for securing the pin in the proper position of adjustment.

Merely by way of example, the bar 10 is illustrated as connected to a slide 30 carrying a crank pin 32 for adjustment radially of a crank disk 34 thereby to vary the throw of the crank pin in accordance with the position of the slide. The outer end of the bar 10 is provided with a pin 36 received in a slot 38 in a block 40 on the outer end of the slide 30, the slot being curved to permit movement of the block out of engagement with the pin upon rotation of the crank disk. Thus it will be seen that as the member 16 is moved its motion will be transmitted through the rolls 24 to the bar 10 whereby the slide 30 may be ad-

justed radially of the crank 34 to vary the position of the crank pin. The use of the rolls between the actuating member 16 and the bar 10 forms an efficient power transmitting mechanism in which little energy is lost through friction and in which there is no lost motion between the members. It will be evident that the rolls 24 may be substituted by balls if desired. Such use of balls in place of the rolls is shown in the modification illustrated in Figs. 3 and 4.

These latter figures illustrate a mechanical movement which is the same in principle as that of Figs. 1 and 2 but in which the driven member is movable not only at an angle to the path of movement to the drive or actuating member but in a different plane. A plurality of balls 50 are movable in a tube 52 carried by a block or support 54 the tube being similar in shape to the bore through the support 12 of Fig. 1 but the plane of the tube being inclined in the block as indicated in Fig. 3. The motion of the balls is effected by an actuating member 56 carrying pins 58 engageable with the outermost balls of the series, the pins being adjustably secured to the member 56 by set screws 60.

A bar or driven member 62 is carried for movement along the upper surface of the block 54 at right angles to the path of movement of the actuating member 56. For thus guiding the bar 62 a guide 64 is secured by screws 66 to the top of the block 54. The bar 62 carries a depending pin 68 which passes downwardly through a slot formed in the block and communicating with a slot 70 (Fig. 4) in the tube 52. The lower end of the pin 68 is received between a pair of the balls 50 so that upon movement of the balls by the actuating member 56 motion is transmitted through the pin 68 to the bar 62 which is thus moved in a direction at right angles to the direction of the actuating member 56 and in a different plane.

From the above it will be seen that a very simple, easily assembled antifriction mechanical movement is provided in which motion is transmitted from one member to another member for movement along a path at an angle to the path of movement of the first member.

Having thus described the invention, what I claim as new and desire to secure by Letters Patent of the United States is:

1. In combination, a member arranged to be moved along one path, a member movable along a path at an angle to the path of movement of the first named member, and means for transmitting movements of one member to the other member comprising a series of antifriction elements, means for confining said elements for movement along a path an intermediate portion of which is in the direction of movement of one of said members and the outer portions of which extend in the direction of movement of the other member, means carried by said one of said members projecting between a pair of said elements in the intermediate portion of the path, and means carried by the other of said members engageable with the outermost elements of the series.

2. In combination, a member arranged to be moved along one path, a member movable along

a path at an angle to the path of movement of the first named member, and means for transmitting movement of one member to the other member comprising a support having a bore therethrough, a series of antifriction elements confined for movement along said bore in a path, an intermediate portion of which is parallel to the direction of movement of one of said members and the outer portions of which are parallel to the direction of movement of the other of said members, means connecting one of the elements in the intermediate portion of the path to one of said members, and means carried by the other of said members engageable with the outermost elements of the series.

3. In combination, a support, a member slidably carried by the support for movement along one path, a second member slidably carried by the support for movement along a path at an angle to the path of movement of the first named member, said support having a bore therethrough the outer ends of which are parallel to the path of movement of one of said members, an intermediate portion of said bore being parallel to the path of movement of the other of said members, a series of antifriction elements in said bore, means carried by one of said members engageable with the outermost elements in said bore, and means carried by the other member extending into an intermediate portion of the bore between a pair of said elements.

4. In combination, a support, a member carried by the support for movement along one path, a second member slidably carried by the support for movement along a path at an angle to the path of movement of the first named member, said support having a bore therethrough the ends of which are parallel to the path of movement of the first named member and an intermediate portion of which is parallel to the path of movement of the second member, a series of rolls in said bore in side-by-side relation, means carried by said one of said members engageable with the outermost rolls in said bore, and means connecting the other member to one of the rolls in the intermediate portion of the bore.

5. In combination, a support, a member slidably carried by the support for movement along one path, a second member slidably carried by the support for movement along a path at an angle to the path of movement of the first named member, said support having a bore therethrough the outer ends of which are in alinement and are parallel to the path of movement of the first member, the ends of the bore being connected by a U-shaped loop, a leg of which is parallel to the path of movement of the second member, a series of antifriction elements in said bore, pins slidable in the outermost portions of the bore engaging at their inner ends the outermost antifriction elements, the outermost portions of said pins being carried by said one of said members, and means carried by the other member extending into said leg of the U-shaped loop of the bore between a pair of said antifriction elements.

SIDNEY J. FINN.
